UNITED STATES PATENT OFFICE

FELIX ALEXANDER JOSEPH, OF HAMPSTEAD, LONDON, ENGLAND

DESIGN FOR A PACK OF PLAYING CARDS

Application filed December 19, 1929. Serial No. 33,839. Term of patent 14 years.

To all whom it may concern:

Be it known, that FELIX ALEXANDER JOSEPH, a subject of His Majesty the King of Great Britain and Northern Ireland, residing at 43 Hollycroft Avenue, Hampstead, London, N. W. 3, England, has invented a new, original, and ornamental Design for a Pack of Playing Cards, of which the following is a specification, reference being had therein to the accompanying drawing, forming a part thereof, on which the figures are face views of a pack of playing cards, showing my new design.

I claim:

The ornamental design for a pack of playing cards substantially as shown.

Dated this 26th day of November, 1929.

In testimony whereof, I have affixed my signature.

F. A. JOSEPH.
